WIRE TYING MACHINE

Wilhelm Jansen, deceased, late of Munchen-Gladbach, Germany, by Elisabeth Jansen, widow and heir and guardian of minor heirs, Munchen-Gladbach, Germany

Application November 20, 1951, Serial No. 257,381

Claims priority, application Germany December 9, 1950

11 Claims. (Cl. 140—93.6)

The present invention relates to a wire tying machine, by which I mean a device for tensioning a length of binding wire about a package, carton, box or the like, for intertwisting portions of the wire to fasten the wire securely while tensioned, and for cutting away any excess portions of the wire length. More particularly the invention relates to a device of this nature in which operation of a single lever brings about these three essential steps of wire tying, i. e., tensioning, twisting, and cutting, in the proper sequence.

Previously known devices of this kind have the disadvantage that it is either difficult or impossible to have the working processes occur successively in the necessary way if a perfect fastening is to be achieved. The maintenance of the correct sequence is essential in order to obtain perfect fastening. For example, if the cutting-off step takes place before the twisting tension is released, at the fastening, the short ends then left at the fastening will be bent outwards by the twist which accompanies the release of tension, and will stick out. Such fastenings are apt to cause injuries and should therefore be avoided.

As another example, if the tension is reduced on the spreading tools which maintain the tension in the loop of wire before the ends are cut, but at the same time the applied twist is maintained, the ends will turn up when they are cut and will stick out as in the preceding example.

Another defect of the known machines is their unwieldy nature, which prevents them from being used to best advantage. This defect is present, for example, when the functions are divided among several separate units. Duplication of lever strokes, large play, etc., also serve to reduce the efficiency.

The object of the invention is to produce a wire tying machine operated by a single lever, in which the individual work processes are accurately maintained with very simple means and can be synchronized with one another. At the same time, even an unskilled workman will be able to break down the machine into just two parts in order to clean and lubricate all the parts.

Quite generally, these objects may be achieved by a special arrangement of various parts, which can be wholly adopted from present-day technique. Hence the achievement of the stated aims is possible merely by re-arrangement of these parts. Such a re-arrangement consists in having the operating lever actuate one or both tensioning levers with the aid of suitable parts during the first part of its forward movement, wire gripping mechanisms of conventional design being attached to the ends of the tensioning levers. In the second part of the forward movement, either after the tensioning step is completed, or better, just before its completion, the twisting pinion is set in operation. With this preferred order, at the end of the forward motion of the operating lever, the binding is not only tensioned as in the case of conventional devices, but the binding is also fastened by the intertwisting given to the overlapped wire portions in the slot of the twisting pinion during the rotation imparted to the latter.

During the return stroke of the operating lever the twisting pinion is stationary, i. e., it is locked, and the transmission parts which cause it to turn are free with respect to the operating lever during its return stroke. On the other hand the moving parts which operate the tensioning lever or levers, are caused to operate on the return stroke, so that during this stroke the tensioning equipment returns to its original position. However, before the tension is released during the return stroke, one or two cutting blades are actuated by the operating lever so as to cut off the ends of the wire. Thus the wires are cut off before the tension is released, and the formation of projecting ends is thereby avoided.

It should perhaps be pointed out at this time that the working parts (which, as already noted, may be constructed, to begin with, on the basis of present day practice) are to be so dimensioned that adequate motions are obtained. In the case of the tensioning operation, for example, sufficient tension must be attainable in the wire even where lengthy bindings are involved. To this end allowance is made for differences in the lengths of bindings and of tension paths by means of a spring loading of one or both of the arms which carry the wire gripping mechanisms.

Further, the motion of the twisting pinion must be so calculated that the entrance slot is always open to the front again at the end of the twisting process, and that it is held in this position by some means, such as a ratchet and pawl mechanism or the like, during the return stroke of the operating lever. The tensioning motion may be imparted, for example, by one or two cam faces on a cam connected to the lever, and a cooperating cam follower on each tensioning lever, the number of these cam faces and followers being dependent on the number of tensioning levers to be actuated. Thus if there is only one movable tensioning lever, the other wire gripping mechanism being fixed, then naturally only one cam face and cooperating follower will be necessary.

The wire tying machine of my invention may be broadly defined as comprising a housing, a reciprocable operating lever, a pair of tensioning levers pivotally mounted within the housing, an arm pivotally mounted upon each tensioning lever, the points of pivotal mounting of said arms being intermediate the ends thereof, corresponding ends of said arms being linked to one another by tension spring means, each of said arms carrying a wire gripping mechanism at the end thereof remote from said spring means, at least one cam rigidly secured to said operating lever, a slotted twisting pinion rotatably mounted in said housing, a gear wheel meshing with said pinion, at least one pivotally mounted wire cutting blade, and a ratchet wheel rotatably mounted with respect to said cam, said gear wheel being rigidly secured to said ratchet wheel. Means are associated with said cam for spreading apart the ends of said arms carrying the wire gripping mechanisms during the initial stage of a forward stroke of said operating lever. Means are associated with said cam for actuating said ratchet wheel and hence said gear wheel and pinion during a later stage of forward movement of said operating lever. Furthermore, means are associated with said ratchet wheel for holding said ratchet wheel and hence said gear wheel and pinion stationary during a return stroke of said operating lever, and means are provided in association with said cam for actuating said cutting blade during the return stroke of said operating lever.

In the drawings which illustrate an embodiment of the invention:

Figure 1 is a longitudinal section through the centre of a binding apparatus according to the invention;

Figure 2 is a section along the line II—II of Figure 1;

Figure 3 is a section along the line III—III of Figure 1;

Figure 4 is a section along the line IV—IV of Figure 3; and

Figure 5 is a section along the line V—V of Figure 1. As evident from the drawings, in the turtle-shell shaped housing 10, axle 12 (Figure 3), bent from a steel rod, is mounted and is integral with operating lever 11. The end of the lever is provided with a knob 13 for convenient gripping, and to permit easier handling of the device another knob 14 is fastened to the rear of the housing for the other hand to grip. A cam 15 is rigidly secured to the axle 12 and carries cam faces 16. The shapes of the cam faces 16 on either side are shown particularly in Figures 2 and 3. In the central plane of cam 15 a gear wheel 17 is mounted which rotates freely with respect to the axle 12. A ring-like ratchet wheel 18 is rigidly secured to gear wheel 17. As may be best seen in Figure 5, gear wheel 17 and ratchet wheel 18 are secured against axial displacement by a bifurcated guide piece 19. Gear wheel 17 meshes with a twisting pinion 20, which, as shown in Figures 2 and 3, is journalled in two bearings 21, the bearings being secured to the base plate 54 of housing 10 by screws 22 which also serve to secure base 54 to housing 10. Twisting pinion 20 is slotted (at 25) in the conventional manner for the reception of the wire portions which are to be intertwined.

From Figure 1 it can be seen that ratchet wheel 18 has three inner free-run notches 23 spaced at intervals of 120°, and three outer notches 24, also spaced at intervals of 120° C. Ratchet wheel 18 is shown in its position of rest, with entrance slot 25 of twisting pinion 20 opening to the front. A pin 26 is disposed in a radial bore 27 in cam 15, and is urged outwardly by the action of a compression spring 28, which biases the end of the pin against the inner periphery 29 of the ratchet wheel 18.

Pin 26 is disposed midway between two of the free run notches 23 when the ratchet wheel is in its position of rest. When the lever 11 is swung forwardly, driving cam 15 (and therefore pin 26) in the direction of arrow 30 (Figure 1), the pin must travel through the 60 degrees which separate it from the nearest notch (in the direction of arrow 30) before motion is imparted to the ratchet wheel 18. Thus, when operating lever has been turned forwardly through 180 degrees, ratchet wheel 18 will only move through 120 degrees. As will be more fully explained hereinafter, ratchet wheel 18 is held against movement during the return or backward stroke of the operating lever, while pin 26 will of course be carried back through 180 degrees during the return movement and will therefore once again occupy a position midway between two of the notches 23. Notches 23 are so formed that when pin 26 enters a notch during a return stroke of the operating lever, it will ride out of the notch rather than jamming against a wall thereof. It will be appreciated that each complete reciprocation of the operating lever 11 results in a movement of ratchet wheel 18 through 120 degrees in the direction of arrow 30, so that three reciprocations serve to give ratchet wheel 18, and the associated gear wheel 17, a complete revolution.

The means for holding ratchet wheel 18 against movement during the return stroke of the operating lever will now be described. A pawl 31 is mounted on housing 10 by means of bolt 32 and is subjected to the pull of a tension spring 36, which is hooked at one of its ends to a projection 33 extending from the pawl, and at its other end to a ring 35. Ring 35 is secured adjacent the rear under surface of housing 10 by means of a bolt 34 which also serves to mount the hand-grip knob 14. Pawl 31 is shown at its position of rest in one of the notches 24. Pawl 31 is so designed in relation to the notches 24, that movement of ratchet wheel 18 is blocked in the direction opposite to that designated by arrow 30, i. e., during the return stroke of the operating lever, so that the gear wheel 17 and the twisting pinion 20, are held stationary, whereas during the forward motion (motion in the direc-

tion of arrow 30), the action of the corner 37 of the notch 24 in the ratchet wheel 18 upon the slanting surface 38 on the underside of the pawl 31 lifts the pawl out of the notch, thus acting against the tension of spring 36. As will be readily understandable the number and the spacing of the teeth on gear wheel 17 and twisting pinion 20 must be so chosen that the 120 degrees of movement of gear wheel 17 which occurs during the reciprocation of the operating lever imparts a number of substantially complete revolutions to the pinion so that the slot 25 therein will be correctly aligned, i. e., opening forwardly, upon completion of the operation.

Cam faces 16 of cam hub 15 are so designed that, as shown in Figure 2, two tensioning levers 39, each of which is pivotally mounted in the housing as indicated at 40, and which are drawn towards each other, by two tension springs 41, make contact with these faces through rollers 42. (See also Figure 3.) The cam faces 16 occupy more than 60° of the circumference of the faces of the cam 15.

Tensioning levers 39 support double-armed clamping levers 43 which are pivotally mounted, as indicated at 44, at the outer ends of the tensioning levers 39. Clamping levers 43 consist of rearwardly extending arms 45 and forwardly extending arms 47. Rearwardly extending arms 45 are linked by springs 41, which, therefore, act on tensioning levers 39, not directly, but indirectly through these arms. Plates 46, punched and pressed outwards from the tensioning levers 39, serve as stops for the arms 45 of clamping levers 43 and limit their motion toward one another. Wire gripping mechanisms 48 and 49 (of conventional design) are attached to the forward arms 47 of clamping levers 43. The arrangement is such that the tensioning motion, even with large bindings and soft packages is sufficient, while, for tying smaller boxes for example where only a short tensioning path is possible, springs 41 prevent breaking of the binding wire, and clamping devices 48, 49 do not separate any further, despite the further outward motion of tensioning levers 39, because the clamping levers 43 execute a rotary motion, the outer ends of arms 47 moving toward one another.

As may be noted in Figure 3, slotted guide plates 50 are disposed flushly against the opposite ends of the twisting pinion bearings 21, the plates 50 being rigidly secured to the bearings 21. At the side of each slotted guide plate 50, a cutting blade 52 is pivotally mounted with respect to each bearing 21 by means of screws 51 (see Figures 3 and 4). Cutting blades 52 are normally urged to a position which clears the slots in guide plates 50, i. e. to an open position, by the action of springs 53.

One end of spiral spring 53 enters the cutting blade 52 and the other end bears against the base plate 54. Arms 55 extend from cutting blades 52. These arms 55 have a flat edge portion 56 which, in the open position, rests against axle 12, so that the axle constitutes a stop for the blades. The upper front portions of arms 55 are tapered as may be noted in Figures 3 and 4. The cam 15, as may be seen in Figures 1, 3 and 4 has a longitudinal bore 59, in which are lodged two solid cylindrical pins 60, which are normally urged outwardly away from one another by a cylindrical compression spring 61 of similar or somewhat smaller diameter than the pins 60. These pins normally bear against plates 62 rigidly secured to the inner side walls of the housing 10. Pins 60 have slightly convex end faces 63, so that, with rotation of the cam 15 in the direction 30 (Figure 1) they are forced inwards in bore 59 as they pass over the tapered faces 58 of arms 55. After the operating lever 11 and hence the cam 15 have been turned through 180 degrees, pins 60 are urged by spring 61 to once again bear against the plates 62 (Figure 4), at which time they occupy positions rearward of flat edge portions 56 of the arms 55. During the return stroke of lever 11, since thickness of arm 55, as Figure 3 shows, is considerably greater than the convexity of end faces 63

of the pins 60, the arms 55 are deflected forwardly and downwardly by the pins 60 forcing cutting blades 52 to sweep across the slots in guide plates 50, cutting away the excess portions of wire. Stop ledges 64 extend from housing 10 and are provided to impose a limit upon the movement which may be given lever 11, the limit being imposed when the pins 60 meet the ledges 64.

In the case of the wire tying machine described above, during the forward stroke of operating lever 11, longitudinal tensioning of a wire binding (wound about a package and gripped in mechanisms 48 and 49) occurs during approximately the first 70° of forward motion, twisting of the wire through rotation of pinion 20 occurs during about 120° of the forward motion, and about 10° of the forward motion are devoted to "overtwist." By "overtwist," I refer to the fact that I preferably employ gearing which rotates the twisting pinion somewhat more than a whole number of revolutions during a forward stroke of the lever, to compensate for the springiness in the wire binding material. During the return stroke of the lever 11, the first 10° of motion are devoted to release of overtight, cutting takes place within the next 120°, and during approximately 70° of the return stroke, release of tension occurs, i. e. levers 39 are permitted to return to the position shown in the drawings. Preferably, about 10° of play is provided between pawl 31 and the adjacent notch 24 in the outer periphery of the ratchet wheel 18 when the operating lever 11 has been rotated to its most forward position. I prefer to describe my lever arm 11 as rotatable through approximately a half-circle. Where no overtight is employed, the half-circle will usually be a true half-circle of 180°; but where overtight is employed the lever will usually be rotatable through about 200° and there will be a smooth succession of the three forward and the three rearward wire tying steps. Even in the latter (overtight) case, a rotational limitation of 180° may be in effect, this being made possible by a shortening of some of the tying steps, particularly the tensioning, twisting and tension releasing steps.

What I claim as my invention is:

1. In a wire tying machine, a housing, a reciprocable operating lever, a pair of tensioning levers pivotally mounted within the housing, aligned wire gripping mechanisms carried by said respective tensioning levers, at least one cam rigidly secured to said operating lever, a slotted twisting pinion rotatably mounted in said housing between said mechanisms, a gear wheel meshing with said pinion, at least one wire-cutting means including a wire cutting blade, a ratchet wheel rotatably mounted with respect to said cam, said gear wheel being rigidly secured to said ratchet wheel, means associated with said cam for spreading apart the ends of said tensioning levers carrying the wire gripping mechanisms during the initial stage of a forward stroke of said operating lever, means associated with said cam for actuating said ratchet wheel and hence said gear wheel and pinion during a later stage of forward movement of said operating lever, means associated with said ratchet wheel for holding said ratchet wheel and hence said gear wheel and pinion stationary during a return stroke of said operating lever, and means associated with said cam for actuating said cutting blade during the return stroke of said operating lever, prior to release of said spread-apart tensioning levers.

2. A wire tying machine as defined in claim 1, in which said spreading means includes two cam faces formed in opposite sides of said cam, and a cooperating cam follower mounted upon each of said tensioning levers.

3. A wire tying machine as defined in claim 1, in which said means for holding said ratchet wheel stationary includes a plurality of notches formed in the outer periphery of said ratchet wheel and a pawl rotatably mounted within said housing and spring-urged to bear against the outer periphery of said ratchet wheel, the edges of said notches and the portion of said pawl which bears against said ratchet wheel co-operating to permit rotation of said

ratchet wheel during a forward stroke of said operating lever but blocking movement of said ratchet wheel during the return stroke of said operating lever.

4. A wire tying machine as defined in claim 1, in which said means for actuating said ratchet wheel includes a plurality of notches on the inner periphery of said ratchet wheel, a pin disposed in a substantially radial bore in said cam, and spring means normally urging said pin outwardly in said bore to force said pin to bear against the inner periphery of said ratchet wheel and enter said notches whenever relative movement of said cam and said pin aligns the pin with one of the notches.

5. A wire tying machine as defined in claim 1, in which two pivotally mounted cutting blades are provided and the means for actuating said cutting blades includes a pair of pins mounted in a bore extending transversely through said cam, a compression spring disposed in said bore between said pins and urging said pins outwardly from said bore, a pair of guide plates rigidly secured to the inner wall of said housing, said guide plates being disposed so as to limit movement of said pins outwardly of said bore, arms extending upwardly from said pivotally mounted cutting blades, the upper ends of said last mentioned arms being tapered and the outer ends of said pins being of convex shape, said tapered ends permitting said pins to ride past the arms of said cutting blades during the forward motion of said operating lever, whereupon said compression spring urges said pins to occupy positions from which they will strike the arms of said cutting blades and rotate said blades during the return stroke of said operating lever.

6. A wire tying machine as defined in claim 1, in which stop means are provided whereby said operating lever may only be turned forwardly or rearwardly through an approximate half-circle, approximately the first 70° of forward motion of said operating lever causing spreading of said levers carrying said wire gripping mechanisms and hence imparting tension to a wire binding held by said gripping mechanism, about 120° of the forward motion of said operating lever causing rotation of said twisting pinion, about 10° of overtight being imparted to binding wire held in the slot in said pinion, approximately the first 10° of the return stroke of the operating lever being devoted to release of overtight, actuation of the cutting blade taking place within the succeeding 120° of return movement of the operating lever, and approximately the last 70° of said return motion being applied to the release of tension.

7. A wire tying machine as defined in claim 1, in which said means for holding said ratchet wheel stationary includes a plurality of notches formed in the outer periphery of said ratchet wheel and a pawl rotatably mounted within said housing and spring-urged to bear against the outer periphery of said ratchet wheel, and in which about 10° of play is provided between the pawl and the adjacent notch in the outer periphery of the ratchet wheel when the operating lever has been rotated to its most forward position.

8. A wire tying machine as defined in claim 1, in which an axle is formed integrally with the operating lever by bending a portion of the latter through substantially 90°, and in which said axle is mounted in said housing with its longitudinal axis parallel to the axis of rotation of said pinion and co-axial with the axes of rotation of said gear wheel and said ratchet wheel, said cam being rigidly secured to said axle.

9. A wire tying machine as defined in claim 1 in which three notches are provided in the inner periphery of said ratchet wheel, said notches being spaced 120° apart from one another, and three notches are provided in the outer periphery of said ratchet wheel, said last mentioned notches also being spaced 120° apart from one another.

10. A wire tying machine as defined in claim 1, in which stop members extend from each of said tensioning levers to impose a limitation upon the movement imparted to said wire gripping mechanisms.

11. A wire tying machine as defined in claim 1, in which the means for holding said ratchet wheel stationary during a return stroke of said operating lever comprises a pawl, in which the housing is in the form of a shell and a base plate, the base plate and shell being detachably connected to one another; in which both the operating lever and the pawl are supported by the shell; and in which said twisting pinion, said cutting blade, and said tensioning levers are mounted upon said base plate.
